UNITED STATES PATENT OFFICE

2,069,961

AIR CONDITIONING APPARATUS

Joseph A. Martocello, Philadelphia, Pa.

Application October 31, 1934, Serial No. 750,879

8 Claims. (Cl. 261—9)

My invention relates to air conditioning apparatus adapted for purifying the air, for varying the amount of humidity in the air, and for controlling the temperature of the air, for dwellings 5 and other buildings.

The object of my invention is to provide an apparatus for conditioning air, including a novel form of tank for containing water, and providing means within the tank for cooling the water by 10 means of ice.

A further object is to provide an air cabinet for conditioning air by means of the water supplied from the tank, and provide a novel apparatus including a pump for circulating the water from 15 the tank to the cabinet and returning the water to the tank to be again cooled.

A further object is to provide the tank with suitable pipe connections including a drain outlet, an overflow outlet, and a relief valve located 20 between the pump and the air cabinet for relieving the apparatus from excess water pressure and for by-passing the water through the relief valve to the tank.

A further object is to construct the tank with 25 novel means for circulating the water in a circuitous course through the tank for quickly varying the temperature of the water.

A further object is to construct a tank having 30 novel means for insulating the walls of the tank, and for sealing the lid upon the body of the tank.

Further objects and advantages will appear 35 in the following description, it being understood that various changes in form, proportions and minor details of construction may be resorted to within the scope of the appended claims.

For a full understanding of my invention and also to acquire a knowledge of the details of the 40 construction and the means for effecting the results, reference is made to the following specification in which the invention is specifically described and claimed.

Referring to the accompanying drawings:

Fig. 1 is a diagrammatic view illustrating my 45 novel air conditioning apparatus, showing the tank in one room of a building and the air cabinet in another room of the building.

Fig. 2 is an enlarged vertical longitudinal sectional view of the tank containing ice, and showing the pump and other adjuncts associated with 50 the tank.

Fig. 3 is an end elevation of Fig. 2.

Fig. 4 is a vertical section on line 4—4 Fig. 2.

Fig. 5 is a plan view of Fig. 2, partially in section.

In the accompanying drawings, in which like reference characters refer to like parts, 12 represents a tank for containing water. Said tank is constructed in a novel manner for retaining the water at a desired temperature by cooling the 5 water by means of broken blocks of ice 13 inserted in the tank. The tank body comprises inner and outer tanks 17 and 18 formed of non-rust sheet metal. Each tank consists of bottom walls 19 and 20 and vertical side walls 21 and 22 between which 10 is inserted cork 25, or other suitable insulating material.

Top members, or panels 26 are secured upon the walls 21 and 22 by flanges 29 and 30, and insulated from the inner walls 21 by insulating 15 material 31.

The top member 26 forms a horizontal surface upon which is located a lid 32, also formed of upper and lower sheet metal walls 33 and 34, which are held in spaced relation by side walls 35 20 formed of sheet metal, as shown in Fig. 4. The lid also is fitted with cork or other insulating material 37. The lid is hinged to the tank body by hinges 38. Clamping devices 40, and a handle 41 are located on the opposite edge of the lid 25 relatively to the hinges. The lid and the top member 26, of the body of the tank, are sealed by means of a sponge rubber gasket 43, which serves as a non-conductor of heat. Said clamping devices 40 are provided with operating handles 164 for clamping the lid upon the tank. 30

A horizontal ice supporting plate 46 is located within the inner tank 17 and held in spaced relation with the bottom wall 19 of the inner tank by means of cleats 47 and 48 preferably formed 35 of wood. The cleat 47 extends centrally of the inner tank from one end wall of the tank and terminates adjacent to the opposite end wall of the tank, thus forming a passageway 50 for the water to circulate between the supporting plate 40 and the bottom wall of the inner tank. Transverse cleats 48 are secured to the under side of the plate 46 by screws 49. Said cleats are arranged in spaced relation to each other upon the bottom wall of the inner tank and form zigzag 45 passageway 51, through which water is directed below the supporting plate 46, from an inlet opening 52 formed in said supporting plate, and around the bottom of the inner tank and through said zigzag passageways 50 and 51 to an outlet pipe 50 connection 53, as indicated by the arrows Fig. 10.

A screen 54 is located upon the bottom of the inner tank and occupies the entrance to the outlet pipe connection for preventing the passage of foreign particles with the water, as the water is 55

drawn from the tank through said outlet pipe connection.

The supporting plate 46 is provided with an opening 56 located immediately above the screen 54 through which opening the screen is accessible for cleaning purposes. The supporting plate 46 is provided with guides 57, in which is movably mounted a sliding door 58, which fits upon the supporting plate 46 sufficiently tight to prevent the free admission of water through the opening into the passageway below the supporting plate, except through the space or inlet 52, formed in said plate.

A pump 59 is provided for forcing the water from the outlet pipe connection to an air conditioning cabinet 60, hereinafter more fully described.

Said pump 59 is operated by an electric motor 61, connected with the pump by a shaft 62. The pump and motor are side mounted upon a base 63 which in turn is secured to the vertical end wall of the tank 12. There is a pipe connection 65 between the outlet pipe connection 53 and the pump, and a pipe connection 66 from the pump 25 to the cabinet 60. A relief valve 68 is connected by a pipe 69 with said pipe connection 66 from the pump to the cabinet. The relief valve 68 has a pipe connection 70 leading into the tank 12, whereby excess water from the pump will be relieved by the relief valve and returned to the tank.

An overflow pipe connection 71 is connected with the tank and with a drain pipe 12. Upon the inner end of the overflow pipe 71 is an extension nipple 73 located within the water compartment of the tank and said nipple is rotatably mounted upon the overflow pipe 71, and extends at right angles to the length of the overflow pipe. By this arrangement the level of the water within 40 the tank may be varied by setting the nipple at different radial positions relatively to the overflow pipe.

A shut-off valve 75 is connected with the outlet pipe 53 for draining the tank. A lock 78 is provided for holding the valve 75 in the closed position.

The outlet connection 53 from the tank 12 is provided with a check valve 74. Said shut-off valve 75 located between the pipe connection 65 and the overflow connection 71 leading to the drain pipe 12. The shut-off valve 75 is operated by a handle 76 for opening and closing the valve 75. The latter is normally closed except when it is desired to drain the tank and then the valve 55 may be readily opened by means of the handle. Said check valve 74 is provided for preventing water entering the tank through the outlet pipe 53.

The tank is provided with a water gauge glass 60 77 of the usual type, and having pipe connections with the tank at points above and below the desired water level.

The air conditioning cabinet 60 consists of a front wall 80, a back wall 81, end walls 82 and a bottom wall 83. Said walls are covered with heat insulating material 84. There are partitions 85, 86 and 87 positioned vertically within the cabinet and extending from one end wall to the opposite end wall, and forming compartments 88, 70 89, 90 and 91.

The cabinet has a fresh air inlet opening 93 consisting of an air duct 94 adapted to be placed at an open window 95. The duct 94 is provided with a grill 97, containing a screen 98. A damper 75 99 is also provided in the duct 94. The upper

portion of the compartment 88 is closed by a top plate 100, which extends around the upper edges of the cabinet and is provided with a large outlet opening 101. A grill 103 occupies the opening 101. Said grill is provided with deflecting plates 104, supported by horizontal bars 105. Dampers 106 are also provided upon the grill 103.

A V-shaped screen 107 is located in the compartment 88 for retaining all foreign particles which may pass through the screen 98.

The first partition 85 terminates in spaced relation with the bottom wall 83 and directs the air from the inlet opening 93 through the first compartment 88 to the bottom of the cabinet where the air is admitted to the second compartment 89 formed by the second partition 86 which is sealed at its lower edge to the bottom wall 83 and its upper edge terminates in spaced relation with a deflector plate 109, having one edge joined with the top of the cabinet and its other edge joined with the top edge of a third partition 87.

The air is directed upwardly through the second compartment 89 and passes over the second partition 86 into the third compartment 90, through which latter it is directed downwardly to the 25 lower edge of the third partition 87 which terminates in spaced relation with the bottom wall 83 and arranged for directing the air horizontally and then upwardly through the fourth compartment 91, from which the air passes through the 30 outlet opening 101 at the top of the cabinet into the room in which the cabinet is located or to other rooms through suitable duct connections, (not shown in the drawings) in a manner well known in the art.

Within the second compartment 89 of the cabinet is located a series of spray nozzles 112 having a pipe connection 113 leading to the nozzles and connected with the service water supply pipe 114 to the building. The nozzles 112 are 40 located in the upper portion of the second compartment through which the air passes upwardly from the bottom of the cabinet toward the nozzles. The water from said nozzles is sprayed against the first partition 85 and thereby forms means 45 for pre-cooling the air as it first enters the cabinet through said first compartment 88.

A second series of spray nozzles 115 is located in the upper portion of the third compartment 90 adjacent to the air passageway located above 50 the upper edge of the second partition 86, whereby the second series of spray nozzles 115 will subject the air to a spray of water as the air passes downwardly through the third compartment.

A pipe coil 118 having radiating fins 119 is 55 located in the fourth compartment 91 and is connected by means of said pipe connection 66 with the pump 59, whereby water supplied by the pump is circulated through the coil 118 and then through a pipe connection 120, which in turn 60 is connected with a pipe connection 121 leading to the second series of nozzles 115. A return pipe 122 is connected with the outlet pipe 120 from the upper portion of the pipe coil 118, and is provided with a valve 123, which may be opened for 65 allowing the water to return from the pipe coil through the pipe connections 122, 127 and 70 to the tank 12.

The pipe connections between the coil 118 and the second series of nozzles 115 are also provided 70 with valves 124 and 125 arranged for controlling or shutting off the water leading to the nozzles 115, when it is desired to return a portion or all the water from the coil directly to the tank by regulating said valves.

The cabinet 60 is provided with a return drain outlet trap 126 having a return pipe connection 127 leading to the inlet pipe 70 communicating with the tank, whereby the spray water from the second series of nozzles 115 will be returned to the tank.

The cabinet is also provided with a drain outlet trap 128 located in the lower portion of the second compartment 89 through which the water from the first series of nozzles 112 may be directed through a pipe 130 leading to the drain pipe 72.

The partition 86 is provided with a float controlled overflow valve 129, which will open in the event that the outlet 126 should become clogged, thus allowing the water to pass through the valve 129 and be discharged through the outlet 128 to the drain pipe 72. Said valve 129 is normally closed.

The cabinet is provided with main air openings 131 and auxiliary air openings 132 and 133 for admitting any desired quantity of air into the cabinet from the room in which the cabinet is located.

The end walls are provided with frames 135 surrounding the main openings 131. Said frames are provided with dampers 136 and screens 138.

The auxiliary air inlet openings or registers 132 and 133 are located upon the front wall of the cabinet for admitting air to the fourth compartment 91. Said inlets are provided with dampers 140 and 141 hinged upon the frames of the registers. Said dampers are arranged to be moved for opening and closing said auxiliary air inlets. One of the auxiliary inlets 132 is located below the pipe coil 118 for admitting air to the lower portion of the fourth compartment 91 so that air from the room in which the cabinet is located may be drawn into the fourth compartment and passed around the coils. The other auxiliary air inlet opening 133 is located above the pipe coil and is arranged for admitting a limited quantity of air into the cabinet from the room, for reducing, or controlling, the amount of the treated air.

A suction and pressure blower 143 is located in the fourth compartment 91 of the cabinet, and is operated by any suitable means such as an electric motor, (not shown in the drawings). A horizontal plate 144 on which the blower is mounted is provided with an opening through which air is drawn by the action of the blower through all the compartments of the cabinet.

A moisture eliminator 146, in the form of screens 147, is located in the passageway adjacent to the bottom wall of the cabinet and below the lower edge of the third partition 87. The screens 147 collect and remove, from the air, excess moisture which has been supplied to the air by means of the spray nozzles. Said screens also provide for the final elimination of impurities from the air.

A strainer 148 and valve 149 are connected in the return pipe 127 and provide means for removing foreign particles from the water before it is returned to the tank. The service water supply pipe 114 is provided with a valve 150 for controlling the flow of water to the nozzles 112.

The air from the blower 143 may be circulated within the cabinet when it is desired to reduce the quantity of air being discharged from the cabinet. The deflector plate 109 is provided with a door 151, which may be opened by a chain 152 and wheel 153, for allowing the air to pass from the blower compartment 91 into the spray nozzle compartment 90 and recirculated within the cabinet. When the wheel 153 is rotated the chain

152 will also release the dampers 106 so that they may move toward the closed position. The wheel 153 is secured upon a shaft 154 extending beyond the end of the cabinet. For normal operation the shaft is turned to a position to open the dampers 106, as shown in dotted lines Fig. 1, and simultaneously close the door 151 upon the deflector plate 109.

The water from the spray nozzles 115 passes through the trap 126 and through the return pipe 127 and 70 to the tank.

The spray nozzles 112 which are connected with the service water supply pipe 114 may be employed for cleaning and purifying the air.

The operation of my invention as an air cooling and conditioning apparatus consists of charging the tank 12 with ice. The melted ice water, or other water, is maintained within the tank up to the water level of the adjustable nipple 73 on the overflow pipe. The cold water in the tank 12 circulates in a zigzag passageway between the plate 46 and the bottom of the inner receptacle of the tank. The ice water is drawn through the screen 54 located at the bottom of the tank, and is forced by the pump to the coil 118 located in the cabinet. The water after circulating through the coil passes to the second series of spray nozzles 115 located in the third compartment 90.

The blower 143 located in the fourth compartment of the cabinet, draws air through the fresh air inlet 93 and through the screen 107 into the first compartment 88 where the air is pre-cooled by the water at its natural temperature from the service water supply pipe connected with the spray nozzles 112. The spray from the nozzles 112 cools the first partition 85 and thereby cools the air as it is drawn downwardly through the first compartment 88. The supply water may be from the city service supply pipe 114 or from a well or any other source for supplying water at a lower temperature than the air that is drawn into the cabinet from without the building. The air is thus precooled as it passes through the first compartment. The air then passes upwardly through the second compartment 89, where it is subjected to the spray of cool water from the first series of nozzles 112 for further cooling the air and also for washing the air, for removing dust and other foreign particles. The air is then drawn into the third compartment 90 in which the second series of nozzles 115 are located and said second nozzles spray ice water into the air for further cooling the air.

Air from the room in which the cabinet is located is admitted to the second compartment 89 of the cabinet through the main air inlet openings 131, for re-cooling and washing the air so admitted from the room. The amount of air admitted through said main inlet openings is controlled by the dampers 136.

From the third compartment 90 the air, and the entrained moisture, are drawn through the moisture eliminators 146 for removing the excess moisture from the air. The air is drawn into the fourth compartment 91 and into contact with the surfaces of the pipe coils 118. Said coils are provided with fins arranged in close parallel relation to each other so that the air passing upwardly through the fourth compartment will pass in contact with the fins and with the pipe coils for further cooling, and also for drying the air due to the ice water which is being circulated through the coils.

The registers located at the auxiliary air inlet 75

openings 132 and 133 in the front of the cabinet provide means for tempering the air by reducing the amount of air drawn from the outside atmosphere and admitting air from the room in which 5 the cabinet is located. By this arrangement large variations in the condition and temperature of the air may be obtained.

The ice water after it passes through the pipe coil and the spray nozzles is returned through 10 the pipe connections to the tank where it is again cooled by coming in contact with the ice and re-circulated from the inlet pipe of the tank to the outlet pipe, which is located in a different portion 15 of the tank relatively to the inlet pipe, so that the water in passing through the tank must pass through the zigzag course formed by the cleats which support the plate 46 on which the ice is supported.

I claim:—

- 20 1. A tank for containing water, a lid detachably sealed upon the tank, a horizontal plate located within the tank, said plate having a hole formed through the same for the passage of water, cleats supporting said plates in spaced relation with the bottom of the tank, said cleats arranged in staggered relation to each other and forming a zigzag water course below said plate, and pipes connected with said tank above and below said plate.
- 30 2. A tank for containing water, a lid detachably sealed upon the tank, a plate positioned horizontally within the tank, said plate having a hole formed through the same and located at one end portion of the tank, a cleat positioned between 35 the bottom of the tank and said plate, said cleat terminating in spaced relation with the end of the tank opposite to said hole formed in the plate, transverse cleats arranged at opposite sides of the first mentioned cleat, said transverse cleats arranged in staggered relation to each other and 40 forming a zigzag water course below said horizontal plate, and pipes connected with the tank above and below said horizontal plate.
3. A tank, a lid detachably sealed upon the 45 tank, a horizontal plate for supporting ice within the tank, cleats supporting said plate in spaced relation with the bottom of the tank, an outlet pipe connected with said tank and located below said plate, said cleats forming channels through 50 which water is directed in a zigzag course below said plate as the water passes toward said outlet pipe, and a return pipe connected with said tank.
4. A tank, a lid, means for detachably sealing the lid upon the tank, a horizontal plate for supporting ice within the tank, said plate positioned in spaced relation with the bottom of the tank, cleats forming vertical partitions between the bottom of the tank and said plate, said cleats each having a passageway formed at one end 55 thereof for the circulation of water in a zigzag course below said plate, an outlet pipe connected with said tank below said plate, said plate having an opening formed therein located at the opposite end of said zigzag course relatively to said outlet pipe, and a return pipe connected with the tank above said plate.
5. A tank, an ice supporting plate within the

tank, cleats supporting the plate in spaced relation with the bottom of the tank, said cleats arranged to form a zigzag water course below said plate, an outlet pipe connected with the tank and communicating with said water course, said plate having an opening formed therein and located at the opposite end of said water course relatively to the outlet pipe, a screen occupying the entrance to the outlet pipe, said plate having an opening formed therein and located above said screen, 10 and a panel movably mounted upon said plate and arranged for opening and closing the opening located in the plate above the screen.

6. An ice melting tank entirely sealed, a horizontal plate for supporting ice within the tank, 15 said plate positioned in spaced relation with the bottom of the tank, cleats forming vertical partitions between the bottom of the tank and said plate, said cleats each having a passageway formed at one end thereof for the circulation of water in a zigzag course below said plate, an outlet pipe connection with said tank, said plate having an opening formed therein located at the opposite end of said zigzag course relatively to 20 said outlet pipe, a pump, a pipe connection between the pump and said outlet pipe, a pipe coil, a pipe connection between the pump and said coil, and a return pipe connection from the coil to said tank.

7. A tank, an ice supporting plate within the 30 tank, cleats supporting said plate in spaced relation to the bottom of the tank, said cleats arranged to form a zigzag water course below said plate, a lid upon the tank, said plate having an inlet opening located adjacent to one end of said 35 water course, an outlet pipe connected with the tank and located adjacent to the opposite end of said water course, a pump connected with said outlet pipe, a fin-type pipe coil, a pipe connection between the pump and said coil, a series 40 of spray nozzles, a pipe connection between said coil and said nozzles, a shut-off valve in the last mentioned pipe connection, a return drain pipe connection between said coil and said tank, a pipe connection between said nozzles and said 45 return pipe connection, a shut-off valve in the pipe connection between the coil and said return pipe connection, a relief valve, a pipe connection between the relief valve and the pump, a pipe connection between the relief valve and the tank, a 50 drain pipe, and an overflow pipe connection between the tank and the drain pipe.

8. A tank for containing water, means within the tank for varying the temperature of the water, inlet and outlet pipes connected with the 55 tank, means within the tank for directing the water through a circuitous course toward the outlet pipes, a pump, a pipe connection with said outlet pipe, a drain pipe connected with said outlet pipe from the tank, a shut-off valve connected 60 with said outlet pipe, said valve located between said connection with the pump and the drain pipe and arranged for draining the tank by opening the valve, and means associated with the valve for locking the valve in the closed position. 65

JOSEPH A. MARTOCELLO.
